[57] CLAIM

The ornamental design for combined rigid temple and supplemental flexible ear clip, as shown and described.

DESCRIPTION

FIG. 1 is a perspective view of a combined rigid temple and supplemental flexible ear clip showing my new design;

FIG. 2 is a side elevational view thereof;
FIG. 3 is a bottom plan view thereof.

The eyeglass frame front and second temple are shown in broken lines for illustrative purposes only.
The characteristic features of my design reside in the combination of rigid temples and supplemental flexible ear clips.
